Des. 194,047
Patented Nov. 13, 1962

194,047

TOY STILT

Anna Belle Hewing, 140 N. Wood St., Chicago, Ill.

Filed Aug. 18, 1961, Ser. No. 66,403

Term of patent 7 years

(Cl. D34—14)

Fig. 1

Fig. 2

Fig. 3

Fig. 4

Fig. 5

Fig. 6

FIGURE 1 is a side elevational view of a toy stilt showing my new design;

I claim:

The ornamental design for a toy stilt, substantially as shown.
